PISTON

Joseph A. Brockmeyer, Brookline, Pa.

Application June 12, 1947, Serial No. 754,144

6 Claims. (Cl. 309—14)

1

This invention relates to a piston of the type used in internal combustion engines, pumps and the like, and the main object of the invention is to produce an improved piston of this type.

A further object of the invention is to produce an improved construction in which the piston is provided with a detachable head provided with parts for receiving conventional piston rings so that, when the rings wear out, they may be replaced with new ones by removing the detachable head but without removing the piston itself from the cylinder.

A still further object of the invention is to produce a piston construction in which the heat dissipation is improved thus making for cooler operation, less breakdown of the lubricant, and less wear.

A still further object is to produce an improved construction in which the upper portion of the piston may be made lighter or of a relatively smaller vertical cross-sectional thickness, as viewed in the drawings, without sacrificing its load capacity.

A still further object is to improve the manner in which the detachable piston head is secured to the piston body.

A still further object is to produce an improved construction whereby, when the worn out rings are replaced a new piston fit is achieved and whereby this may be done at a relatively low cost in replacement parts and in effort.

These and other objects are attained by my invention as set forth in the following specification and as illustrated in the accompanying drawings in which

Fig. 1 is an exploded view of a piston embodying my invention.

Fig. 2 is a vertical sectional view of the piston shown assembled.

Fig. 3 is a top plan view of Fig. 2.

Fig. 4 is a side elevational view of the piston shown in Figs. 1 to 3.

Fig. 5 is a vertical sectional view showing an other embodiment of my invention.

Fig. 6 is a view similar to Fig. 5 showing a slightly modified structure.

Fig. 7 is a top plan view of a clamping ring used in securing the detachable head to the piston body in the embodiment of the invention shown in Figs. 1 to 4.

2

Fig. 8 is a top plan view of a clamping ring used in securing the detachable head to the piston body in the embodiment of the invention shown in Figs. 5 and 6.

5 Referring to Figs. 1 to 4, there is shown a piston having a cylindrical lower skirt portion 10, and a frusto-conical reduced, upper head portion 12, the portions 10 and 12 being connected by a horizontal portion forming a shoulder 14. The piston construction also includes a sleeve 16 having exterior grooves 18 for receiving conventional split rings 20, the sleeve being internally tapered for a snug fit over the frusto-conical portion 12.

Near its top surface 22, the upper portion 12 is provided with a peripheral groove 24 for receiving the resilient split clamping ring 26 of Fig. 7. The ring 26 is so made that, when free, it tends to constrict. The juxtaposed ends of the rings 26 are provided with holes or recesses 28 adapted to be engaged by an expanding type spanner wrench for applying or removing the ring. Thus, when it is desired to apply or remove the clamping ring, the points of the jaws of the spanner wrench are engaged in the recesses 28 and the handles of the wrench are moved in a direction to cause the jaws of the wrench to move apart, thus expanding the clamping ring until it clears the groove 24. The clamping ring may now be removed from, or placed in the groove, as the case may be.

The height of the sleeve 16, that is, the distance between broken lines A and B, and the height of the tapered upper portion 12, that is, the distance between the broken lines C and D, in 35 Fig. 1, are such, in relation to the thickness of the clamping ring and the height of the groove 24 that, when the sleeve 16 is slipped over the tapered portion 12 and the ring 26 is placed in the groove 24, as shown in Fig. 2, the sleeve will 40 be pressed downwardly against the shoulder 14 and against the tapered surface of the portion 12 so that it is held firmly in position against rotation relative to the piston. By this means, the oil holes 30 in the sleeve 16 will be maintained 45 in proper registration with the holes 32 in the piston portion 12. It will be understood that the upper surface 34 of the sleeve 16 and the upper surface 22 of the tapered portion 12 of the piston will be suitably indexed, as at 33, so as to 50 insure initial alignment of the holes 30 in the

sleeve, with the holes 32 in the piston portion 12 during the assembly of the piston.

When it is desired to renew the piston rings, the piston is moved to its uppermost position, the clamping 26 is removed, and the piston is lowered. When this is done the sleeve 16 is detached from the portion 12 of the piston and remains in the upper portion of the cylinder from which it can be readily removed. If the sleeve 16 should stick to the top of the piston and should move down with it, the piston is raised up again, and the sleeve 16 is tapped with a wooden mallet, or the like, to break the bond between it and the top of the piston and the piston is again lowered so as to leave the sleeve 16 at the upper end of the cylinder. In practice, I find that this happens only infrequently. When the sleeve has been removed, the piston is again raised and a new sleeve 16 having new rings 20 is then forced onto the tapered piston portion 12 and is clamped in position by the ring 26. While it is possible merely to replace the worn-out rings, I found, in practice, that it is preferable to use a new sleeve 16 equipped with new rings 20 so as to provide a new piston fit. This is due to the fact that when the grooves 18 wear somewhat, new rings placed in these grooves will be somewhat loosely seated and will, therefore, permit leakage and will cause wear, particularly along the upper and lower edges of the rings.

The taper of the upper piston portion 12 and of the sleeve 16 is such that the area of the upper surface 34 of the sleeve 16 exceeds the area of the upper surface 22 of the tapered piston portion 12. By this arrangement, the surface 22 of the portion 12 is subjected to a smaller portion of the force of the explosion while the surface 34 of the sleeve 16 receives a larger portion of the force of the explosion. Because of this arrangement, the flat top of the upper piston portion can be made thinner, in vertical cross section, without danger of breaking or of caving in. Because the sleeve 16 is supported on the relatively large surface area of the frusto conical portion 12, which has the relatively thick wall 35, it can withstand the major portion of the force of the explosion to which it is subjected. The taper of the portion 12 and of the sleeve 16 is also such as to produce a wedging frictional engagement of an order sufficient to prevent rotation of the sleeve relative to the piston when the clamping ring 26 is in position, without the need of screws or the like for securing the sleeve to the piston.

Furthermore, because the top of the tapered portion is of a relatively small diameter, it can be made of a thinner vertical cross section than would be otherwise possible.

By making the area of the surface 34 of the sleeve 16 bigger than the area of the top 22 of the piston, the sleeve will absorb a larger amount of heat than the piston and, because the sleeve 16 can dissipate its heat more rapidly than the piston can, generally cooler operation will result, thus reducing wear and tear on the contracting moving parts.

In Figs. 5 and 6, there is shown a structure which is identical with that of Figs. 1 and 2 except that the height of the sleeve is equal to the height of the tapered portion 12, so that the surface 34 is flush with the surface 22. To produce this structure, the upper surface 34 of the sleeve 16 is counter-bored, as at 40, to provide room for application and removal of a clamping ring.

In the structure of Fig. 5, I prefer to use a

clamping ring 44, which is clearly shown in Fig. 8. This ring is made of two parts 45 and 46 which are secured in assembled position by interlocking end lugs and recesses 47. This type of ring does not need the room needed for applying and removing the ring 26, and no special wrench is needed. The parts 45 and 46 can be forced into position manually with the aid of a pair of pliers, or the like, and can be disengaged by means of a screw driver or the like.

Fig. 6 also shows that in the structure of Figs. 2 or 5 the top of the piston can be concaved, as at 42.

It will thus be seen that, by providing the shoulder 14, the grooves 24 or 40, the clamping ring 26 and the separable sleeve 16, and by tapering the upper portion 12 of the piston and the sleeve 16 to substantially the proportions shown in the drawings, a light, strong and cool-operating piston is produced. It will also be seen that the sleeve 16 and the ring 20 carried thereby may be removed and installed as a unit and that the removal of the sleeve 16 and the installation of a new sleeve, equipped with new rings, will have the same effect as the installation of a complete new piston.

Having described my invention, what I claim is:

1. A piston comprising a lower cylindrical portion, an upper, frusto-conical portion, a sleeve having an internal, frusto-conical bore adapted to fit over said upper, frusto-conical portion, with at least the inner portion of the top wall of said sleeve disposed below the top wall of said frusto-conical portion, said sleeve also having an outer cylindrical surface adapted to form a continuation of the cylindrical surface of the lower portion of the piston, and means for detachably securing said sleeve to said frusto-conical portion, said means including a groove formed in said frusto-conical portion immediately below the top wall thereof, with the bottom wall of said groove substantially flush with the inner adjacent portion of the top of said sleeve, and a clamping means engaging said groove and said inner adjacent portion of the top of said sleeve to prevent vertical movement of said sleeve relative to said frusto-conical portion.

2. The structure recited in claim 1 in which said clamping means is a split ring and in which the inner portion of said ring engages said groove and the outer portion of said ring overlies the inner adjacent portion of the top of said sleeve.

3. The structure recited in claim 1 in which the base of said upper frusto-conical portion has a diameter smaller than the diameter of the lower cylindrical portion of the piston whereby a shoulder is formed at a right angle to the vertical axis of the piston.

4. The structure recited in claim 1 in which the outer portion of the top of the sleeve, which is not engaged by said clamping means, is flush with the top of said upper frusto-conical portion of the piston.

5. A piston comprising a lower skirt portion, an upper frusto-conical head portion, a sleeve having a tapered internal bore adapted to fit over said head portion and having an external surface adapted to form a continuation of the surface of said skirt portion, the taper of said head portion being such that the area of the top surface of said head portion is less than the area of the top surface of said sleeve, and means for securing said sleeve to said head portion.

6. A piston comprising a lower skirt portion, an upper, hollow head portion formed of a frusto-

conical wall structure and end wall at the smaller end of said frusto-conical wall structure, an annular sleeve having an external surface adapted to form a continuation of the external surface of said skirt portion and having a tapered bore adapted to fit over said frusto-conical wall structure, and means for securing said sleeve to said head portion, the diameter of the end wall of said head portion being relatively small whereby said end wall can be made relatively thin.
